(57) **CLAIM**

The ornamental design for a chair, as shown and described.

DESCRIPTION

FIG. 1 is a front, left perspective view of a chair embodying my new design;

FIG. 2 is a front elevational view thereof;

FIG. 3 is a left side elevational view thereof, the right side elevational view being a mirror image thereof;

FIG. 4 is a top plan view thereof;

FIG. 5 is a rear elevational view thereof;

FIG. 6 is a front, left perspective view of a second embodiment of a chair embodying my new design;

FIG. 7 is a front elevational view thereof;

FIG. 8 is a left side elevational view thereof, the right side elevational view being a mirror image thereof;

FIG. 9 is a top plan view thereof;

FIG. 10 is a rear elevational view thereof;

FIG. 11 is a front, left perspective view of a third embodiment of a chair embodying my new design;

FIG. 12 is a front elevational view thereof;

FIG. 13 is a left side elevational view thereof, the right side elevational view being a mirror image thereof;

FIG. 14 is a top plan view thereof; and,

FIG. 15 is a rear elevational view thereof.

In the drawings, the broken lines depiction of a welt forms no part of the claimed design.
